SUCTION TONSILLECTOME

Filed April 16, 1937

UNITED STATES PATENT OFFICE

2,115,298

SUCTION TONSILLECTOME

Roderick F. Brown, Altus, Okla.

Application April 16, 1937, Serial No. 137,347

6 Claims. (Cl. 128—309)

My invention relates to certain new and useful improvements in suction tonsillectomes and it has for its primary object to provide an instrument of such compact construction and perfect correlation of parts that an operator may remove a patient's tonsils with the greatest possible skill and safety, having at the same time in his control all equipment necessary for the operation.

Further the invention has for an object to provide an instrument which enables the operator, with a single instrument and the use of one hand only, to draw the tonsil from its capsule or resting place in the throat to such position that it may be severed, the tonsil remaining at all times in plain sight of the operator and, due to the special construction of the instrument enable a practically bloodless operation (no bleeding of the tonsil or any part of the throat occurs until the tonsil is actually severed).

Other objects will in part be obvious and in part generally pointed out hereinafter.

To the attainment of the aforesaid objects and ends, the invention still further resides in those novel details of construction, combination and arrangement of parts, all of which will be first fully described in the following detailed description, then be pointed out in the appended claims, reference being had to the accompanying drawing in which,

Fig. 1 is a vertical longitudinal section of the instrument.

Fig. 2 is an assembly of the cutting members of the instrument the view being an inverted plan view of the parts mentioned.

Fig. 3 is a bottom or inverted plan view of the tonsil bowl or cup.

Fig. 4 is a detail plan view of a portion of the instrument showing the valve.

In the drawing in which like numerals of reference indicate like parts in all the figures, 1 denotes the elongated body of the instrument. This entire piece may be constructed of glass or other transparent material, such as "bakelite" for example or it may be made of metal, using a transparent element for the tip or tonsil bowl (see my Patent No. 2,036,998 issued April 4, 1936).

The body 1 has a longitudinal air duct 2. One end of the duct 2 is enlarged to such dimensions and proportions as to form a bowl or cup 3, into which the tonsil is received. The cup is more fully shown in Fig. 3 in which the general contour is outlined by reference numbers 3.

A sheath 4 is formed on the body 1 connecting the cup 3 with a projection 4^x from the body. 55 The sheath is tubular to receive the snare post 5.

The end of the air duct 2, opposite the bowl 3 is provided with a seat 2^x to receive the nipple 7 of an air suction hose 6 which hose attaches to a pump or other suitable means to provide a suction (not shown). The part of the nipple 7 which inserts into duct 2 is tapered so as to make a friction-tight connection. It should be borne in mind that this method of attaching the instrument to the vacuum pump is perhaps the most simple and convenient, yet any other form of 10 nipple and flexible conduit may be employed in the successful operation of the instrument.

At such a position along the course of the air-duct 2, as is most convenient to the operator, is placed the valve 8. This valve is intended to be 15 operated with the index finger, although other positions may be found more convenient for different operators. Therefore the exact location of valve 8 is not considered to be a feature of this invention. The valve 8 is what is commonly 20 called a plug valve; it may be either tapered or straight-bodied. The plug passes through the body 1 laterally and intersects the passage or duct 2. It has a bore 10 of approximately the same diameter as the duct 2, and it is provided with 25 a handle 9 by means of which the valve may be turned to align the bore 10 with duct 2 or close off the passage more or less, accordingly as the valve is turned to one position or another.

The sheath 4 is an integral part of the body 1 30 and is bored to receive the snare post 5, the snare post passing through a stuffing box of which 11 is a packing of suitable material which is pressed into position by gland 12. By this means loss of vacuum is prevented. The snare post 5 is secured 35 to the finger-bar 13 in any approved way as, for example, by the "latch" arrangement shown in Figs. 1 and 2 at 14.

The finger-bar 13 is secured to the body 1 by a bolt 15 which passes between the two loops 18 40 provided for the fingers.

The under face 19 of the body 1 is flat and the finger-bar 13 slides against such flat surface 19, which prevents twisting the bar to undesirable positions. The bolt 15 is threaded at 15^x into 45 the body 1 and passes through an apertured lug 14.

The bolt 15 has a milled head 16 by which it may be turned to screw it into the body at 15^x. Beyond the head 16 there is swivelly mounted 50 on a projection of the bolt, a thumb loop 17 (see Fig. 1).

The construction of the finger-bar 13 and the snare 20 is most clearly shown in Fig. 2 by reference to which it will be observed that the bar 55

13 has two loops or eyes 18 into which the index and second fingers pass. The snare post 5 is connected to bar 13, at 14, as before described. The end of the post 5 is flattened on opposite sides and holes 21 are drilled through the flattened portions to receive the ends of the snare wire 20. Snare wire 20 is a fine gauge metal wire having enough spring quality that it will retain a circular form when placed in the instrument.

10 A groove 22 (see Figs. 1 and 3) is provided in the bowl 3 to receive the snare 20. Thus, due to the spring quality of the wire 20, it is held in groove 22 and allows the tonsil to pass into bowl 3.

Operation

15 In operation the instrument is first made ready for use in the following manner: Assuming the instrument to be assembled except for the snare wire 20 and the hose and nipple 6 and 7 respectively. The finger-bar 13 is exposing holes 21.

20 A piece of snare wire 20 of the proper length and having the ends properly crimped to facilitate threading is attached to post 5 in the manner shown in Fig. 2. Finger-bar 13 is now pulled back and adjusted to such a position that snare 20 is in its proper position in the groove 22; packing gland 12 is now tightened enough to insure against leakage. Hose nipple 7 is inserted in air-duct 2 and given a slight twist so that it tightens

25 in a position where the hose 6 will hang in a natural and convenient position for the operator. The instrument is now held in the operating position, which is with the thumb extending vertically thru thumb loop 17 and with the index

30 and second fingers in loops 18. The hose 6 should now be hanging so as to pass through the palm of the hand. With the valve in the closed position and the suction pump in operation, the instrument is passed into the patient's throat which

35 has been properly prepared for the operation. With the fingers of his free hand on the outside of the patient's throat the operator presses in the vicinity of the tonsil, thus assisting in raising the tonsil so that the cup 3 of the instrument

40 may be placed directly on the tonsil. When the instrument is properly placed over the tonsil the valve is opened and the tonsil allowed to be drawn into the cup by the action of the pump. The operator can see the tonsil through the

45 walls of the cup and can tell when the proper position is obtained to sever the tonsil, which is done by merely clinching the hand.

50 From the foregoing description taken in connection with the accompanying drawing it is thought the construction, operation and advantages of the invention will be clear to those skilled in the art.

55 What I claim is:—

1. In a tonsillectome an elongated body having at one end a tonsil bowl to receive a tonsil, said body having an air duct extending from end to end and communicating at one end with said bowl and having means for the attachment of a suction duct at the other end of said air duct, a removable bolt carried by said body, a finger-bar slidably mounted on said bolt, a snare post, a sheath carried by said body for said post, means by which said post is connected at one end to said finger-bar, a snare carried by said post at the other end said snare projecting into said bowl when not in action, and a valve carried by said body to control passage through said air duct.

70 2. In a suction tonsillectome, a body having a tonsil receiving bowl at one end and having an

air duct in connection with said bowl and having provision for the connection of said duct to a suction line, a valve carried by said body to control passage through said duct, said body having a flat underface, a finger-bar having finger loops and located in contact with said flat underface, means carried by said body beneath said flat underface for slidably sustaining said finger-bar, a sheath carried by said body and extending rearwardly from said bowl parallelly beneath said body and having a bore one end of which communicates with said bowl, a stuffing box at the other end of said bore and a snare post held in said sheath and passing through said stuffing box and being connected to said finger-bar, said snare post adjacent said bowl carrying a snare, the finger-bar carrying means aforesaid comprising a bolt, said body having lugs through one of which said bolt passes and is screwed into the other one of which, said finger-bar having a bore through which said rod passes.

75 3. In a suction tonsillectome, a body having a tonsil receiving bowl at one end and having an air duct in connection with said bowl and having provision for the connection of said duct to a suction line, a valve carried by said body to control passage through said duct, said body having a flat underface, a finger-bar having finger loops and located in contact with said flat underface, means carried by said body beneath said flat underface for slidably sustaining said finger-bar, a sheath carried by said body and extending rearwardly from said bowl parallelly beneath said body and having a bore one end of which communicates with said bowl, a stuffing box at the other end of said bore and a snare post held in said sheath and passing through said stuffing box and being connected to said finger-bar, said snare post adjacent said bowl carrying a snare, the finger-bar carrying means aforesaid comprising a bolt, said body having lugs through one of which said bolt passes and is screwed into the other one of which, said finger-bar having a bore through which said rod passes.

80 4. In a suction tonsillectome, a body having a tonsil receiving bowl at one end and having an air duct in connection with said bowl and having provision for the connection of said duct to a suction line, a valve carried by said body to control passage through said duct, said body having a flat underface, a finger-bar having finger loops and located in contact with said flat underface, means carried by said body beneath said flat underface for slidably sustaining said finger-bar, a sheath carried by said body and extending rearwardly from said bowl parallelly beneath said body and having a bore one end of which communicates with said bowl, a stuffing box at the other end of said bore and a snare post held in said sheath and passing through said stuffing box and being connected to said finger-bar, said snare post adjacent said bowl carrying a snare, the finger-bar carrying means aforesaid comprising a bolt, said body having lugs through one of which said bolt passes and is screwed into the other one of which, said finger-bar having a bore through which said rod passes, and a thumb loop carried on the free end of said bolt.

85 5. In a suction tonsillectome an elongated body having a tonsil receiving bowl at one end and an air duct connecting with said bowl and extending therefrom toward the other end with provisions for connecting to a suction line, said body having two apertured lugs on the under side between which lugs the underface of the body is flat, a valve carried by said body to control passage through said air duct, one of said lugs having a threaded cavity and a bolt passing through one lug and threaded into said cavity, a finger-bar

- slidably mounted on said bolt and engaging the flat underface of said body, a snare post extending through the aperture of said threaded lug, a sheath between said bowl and said last named lug through which sheath said snare post passes, a snare connected to the bowl end of said post and normally lying in said bowl, means connecting said post to said finger-bar and means to prevent air passing through said sheath.
- 5 6. In a suction tonsillectome an elongated body having a tonsil receiving bowl at one end, an air duct connecting with said bowl and extending therefrom toward the other end with provisions for connecting to a suction line, said body having two apertured lugs on the under side between which lugs the underface of the body is flat, a
- 10 valve carried by said body to control passage through said air duct, one of said lugs having a threaded cavity and a bolt passing through one lug and threaded into said cavity, a finger-bar slidably mounted on said bolt and engaging the flat underface of said body, a snare post extending through the aperture of said threaded lug, a sheath between said bowl and said last named lug through which sheath said snare post passes, a snare connected to the bowl end of said post and normally lying in said bowl, means connecting said post to said finger-bar and means to prevent air passing through said sheath, said bolt having an extension at its free end and a thumb loop rotatably mounted on said extension.
- 15
